UNITED STATES PATENT OFFICE.

VICTOR D. RENWICK, JR., OF MERCHANTVILLE, NEW JERSEY.

FOOT-OPERATED VALVE.

1,071,261.

Specification of Letters Patent. Patented Aug. 26, 1913.

Application filed November 4, 1912. Serial No. 729,425.

To all whom it may concern:

Be it known that I, VICTOR D. RENWICK, Jr., a citizen of the United States, residing at Merchantville, in the county of Camden 5 and State of New Jersey, have invented certain new and useful Improvements in Foot-Operated Valves, of which the following is a specification.

This invention relates to improvements in 10 foot operated valves.

The primary object of the invention is the provision of elements designed to render the assembling and dis-assembling of a foot operated valve an easy and rapid operation, 15 including the seating of the spring actuator.

A foot operated valve is covered by my Letters Patent #1,004,467, dated September 26, 1911, and the present invention differs from the same in the specific formation 20 of certain of the elements and in the manner of dis-assembling the parts, while it resembles the same in being foot operated and of the general type known as push button valves. During the service and use of these 25 valves, it is advantageous to provide a ready and easy means whereby the washer and packing carrying parts are readily accessible for the purpose of renewing the wearing elements, and I now provide complete valve mechanisms adapted to be readily 30 inserted and withdrawn from a primary valve body or casing. This provision also includes means for forcing the valve plug from a tapered bore of the casing upon a 35 movement effecting a withdrawal of the general valve elements. There is further provided a serviceable closed form of valve casing having a drainage outlet leading therefrom for exhausting any fluid accumulating 40 around the valve operating mechanism during the operation thereof.

More specific objects of the invention are the provision of a locking means between the stem head and a plug sleeve whereby a 45 forced rotation of the former results in lifting said plug sleeve from the casing.

With these main objects in view and others that will appear as the nature of the invention is better understood, the same 50 consists in the novel combination and arrangement of parts hereinafter fully described, illustrated in the accompanying drawings, and pointed out in the appended claims.

55 In the drawings forming a part of this application and in which like numerals of

reference designate corresponding parts throughout the several views:—Figure 1 is a central vertical longitudinal sectional view of the device. Fig. 2 is a top plan view thereof. Figs. 3, 4, and 5 are horizontal transverse sectional views taken respectively upon lines 3—3, 4—4, and 5—5 of Fig. 1. Fig. 6 is a side elevation of the device upon a reduced scale. Fig. 7 is a related view of a portion of the stem with the head, the sleeve and the locking carrier therefor. Fig. 8 is a detail view of the engagement between the head and sleeve. Fig. 9 is a perspective view of the locking carrier inverted, and, Fig. 10 is a sectional detail view of a form of coupling for the inlet and outlet.

Referring more in detail to the drawings, a closed substantially tubular valve casing 75 or body 15 is employed having at its lower end inlet and outlet ports 16 and 17 respectively, the latter being of substantially the ordinary construction. Said casing is provided with the top annular flange 18 adapted 80 to receive the casing within an opening of the floor 19 with said flanges seated thereon or in a mortise therein and secured by hold-fast devices 20 if desired. Within the lower part of the casing 15 and including that 85 portion between the inlet and outlet thereof, the inner facing of the casing as at 21 is downwardly tapered for the reception of a correspondingly tapered valve plug 22 which is inserted therein from the open top of the 90 casing. Said plug being provided with a central bore 23, slidably receives the reciprocating valve stem 24 which at its lower end has the annular piston 25 working in the enlarged portion 26 of said bore. Said valve 95 stem at its lower end being provided with a screw-threaded bore is adapted to receive the screw 27 of the cup washer 28, the latter adapted to receive and position the bib washer 29. The plug is normally positioned 100 above the bottom 30 of the valve casing providing the water chamber 31 in the bottom thereof and within the upper portion of which the recessed end 32 of the valve plug extends, the cup washer and bib washer on 105 the lower end of the valve stem being therein reciprocated upon an operation of the valve for seating and unseating said washer from contact with the annular flange 33, at the lower periphery of the enlarged bore 26. 110

The plug 22 upon a plane normally in alinement with the inlet 16 is provided with

the annular recess 34 and from which at 5 four diametrically opposed points inlet ports 35 communicate with the enlarged central bore 26. Corresponding with the normal 10 position of said recess 34, the valve casing is provided with a coöperating annular recess 36 and by which construction, it will be at once evident that the entrance of a fluid through the nipple 16 fills the annular recesses 34 and 36 and from whence the fluid 15 passes through the ports 35, into the recess 26 and thence to the bottom chamber 31 under control of the valve stem washer 29 and from whence it leaves the casing through 20 the outlet nipple 17. The valve plug is further provided with an inclined external annular shoulder 37 and upon which is seated the plug packing 38 in connection with which a slight enlargement of the casing 25 bore at 39 may be provided if desired. Seated around said valve plug and positioned upon the plug packing and adapted for retaining the latter in closed contact with the plug and thereby firmly positioning 30 the plug within the casing, is the tubular plug sleeve 40 provided with side cut-away portions 41 and being externally screw-threaded at the collared top 42 thereof for engagement with the internally screw-threaded portion 43 at the upper end of the 35 valve casing. It is apparent, that as the lower annular collar 45 of said plug sleeve removably fits the slightly contracted bore 46 of the casing, that said contacting elements may be screw-threaded at these points if desired, so that the plug sleeve may have a screw-threaded engagement with the casing at either or both the top and bottom thereof.

40 The plug sleeve, as will be evident, is removable from the casing by unscrewing the screw-threaded engagement therewith and for the purpose of connecting said sleeve with the valve plug so that the latter may be 45 simultaneously acted upon, a jack washer 47 is adapted to be positioned around the contracted shoulder 48 of the plug by inserting the same through the interrupted portion 49 of the plug sleeve and seated upon the bottom collar 45, all of which is made possible by the interrupted side 50 of said washer, as best shown in Fig. 5.

50 The stem packing cap 51 is seated upon the top of the plug and by reason of the 55 convexity of its top forms with the inwardly inclined top 52 of the plug, a packing chamber adapted to receive a packing 53 which may consist of asbestos saturated with vaseline. The bottom annular flange 54 of the 60 packing cap seats thereon a helical spring 55 encircling the stem and normally maintained partly compressed by the stem head 56 retained thereon by the head screw 57.

65 The present manner of securing the head upon the stem by means of the screw 57 and

a plate or carrier 58 and the locking of the head thereby with the plug sleeve to insure a rotation in unison of said sleeve and head, form a material part of the invention. The carrier being provided with the circular perforation 59 adjacent one end thereof communicates with a central longitudinal slot 60 positioned centrally of the carrier and having a circular counter-sunk portion 61 adjacent the said slot and of the same diameter 70 as the stem. The stem is placed through the perforation 59 of the carrier and is slid therealong until the flattened portion 62 is reached upon the stem, whereupon said flattened portion is moved into the slot 60 at 75 which time the countersunk socket 61 will rest upon the lower shoulder formed upon the stem and by tightening the screw 57, it will be evident that all of the elements will be firmly locked together and that the outer 80 ends 63 of the carrier will project from the head sufficient in length to be slidably received within the slots 80 of the sleeve, through the cut-out portions 64 of the depending flange 65 of the head, which head 85 and flange are slidably fitted within the internal smooth bore of the plug sleeve 40.

The portions of the device exposed to view when in operation and included in the showing of Fig. 2 consist of a foot plate or push 90 button member 66 adapted to have inscribed thereon a proper designation for the fluid adapted to be controlled by the valve, such as, the letter H denoting that the valve is employed for hot water and that a pressure 95 exerted upon the plate will cause a flow of the same. A floor plate 67 adapted to encircle the foot plate which latter is slidably received in the open upper end of the valve casing, and the same is preferably 100 only retained therein by a close frictional contact. For preventing the relative turning of the foot plate 66, the same is provided with a radially-extending rib 68 slidably received in the inner slot 69 of the floor plate and positioned a short distance 105 beneath the upper surface thereof.

In the general description of the present device, the assembling of the head upon the stem and positioned within the sleeve has 110 been set forth as well as the locking of the sleeve to the valve plug by means of the jack washer and the positioning of the plug within the tapered bore of the casing. The function of the spring 35 compressed between the head and packing cap has also 115 been set forth in connection with the packing 53 and also the positioning of the sleeve upon the plug packing 38 so that the assembling of the entire elements will be at once 120 apparent and including the positioning of the foot and floor plates.

The general operation of the device is similar to that of other foot operated valves in that a pressure of the foot plate 66 forces 125

downwardly the valve stem and its packing 29 to unseat the valve; this admits fluid through the inlet during the forced compression of the expansion spring 55, which latter returns the valve to a normally closed seated position upon releasing the pressure upon the foot plate. Such novelty is believed to reside in the adaptation of the plug sleeve to be unscrewed from the casing by a turning of the head 56 through the agency of a wrench exerted upon the squared wrench-hold top surface 70 thereof, the turning of said head communicating a similar rotation to the sleeve through the agency 15 of the carrier 58 engaging in the end slots 80. Such an upward movement of the carrier contacts its lower collar 45 with the jack washer 47 which by its engagement with the plug raises the latter simultaneously with 20 said collar so that by unscrewing the collar through the agency of the squared portion of the head, the entire mechanisms within the casing are at once removable for the purpose of repairing the same or renewing 25 the packings and washers, it of course being noted that the floor and foot plates are readily removed and replaced.

It is evident that while I have described the fluid flow from the nipple 16 to the opposite nipple 17, the fluid flow may be reversed in direction if desired. The preferred manner of operation providing an admission of the fluid through the nipple 16 is opposite to the ordinary operation of 35 valves, in that the pressure of the flow is exerted in a direction to open the valve and is against the action of the spring 55. In the usual construction of valve members, such an operation would be inadvisable as tending to place the valve closing member under a constant strain and effecting a leakage of the valve. The present use of the cup washer and bib packing therein, as valve closing members however, furnishes a structure 45 in which this preferred operation is possible without any liability of causing leakage. Among the advantages of providing the fluid flow in this direction is the prevention of any so-called water hammering, 50 all of which is obviated by the water under pressure within the bore 26 forming a hydraulic cushion for the closing valve member, thus preventing any sudden closure thereof and insuring a gradual closing of 55 the valve upon its seat. The last described operation forming one of the advantages of the invention, it is noted that a further important advantage lies in an elimination of the awkwardness of assembling the spring 60 member within the mechanism. The spring 55 being placed over the stem 24 and seated upon the cap flange 54, the head 56 is placed upon the spindle upon said spring and is drawn down to the normal assembled position by seating the screw 57 in its place,

which compresses the spring 55 and retains the same under such normal compression. The dual function of the spring 55 presents a structure in which the same combines to maintain the packing cap 51 normally seated 70 and at the same time maintaining the valve in a normally closed position.

For draining the casing, opposite ports 72 are positioned therethrough substantially at equi-distant points upon the casing between 75 the inlet and outlet ports. One of said drain ports is adapted to remain open while the other is preferably closed by a suitable plug 73 as shown in Fig. 5.

In connection with the carrier 58, it 80 should be noted that the ends 63 thereof may be narrowed to a less breadth than that of the carrier and adapted to slide in narrow top slots of the collar.

In Fig. 10, a union connection is illustrated which may be employed in connection with the inlet and outlet ports when advantageous. In this structure, the nipple 16 having a tapered seat 84 is adapted to seat the head 83 of the service pipe 82 thereagainst by means of the internally threaded compression nut 81 screwed upon the nipple. 90

Having thus fully described my invention and in what manner the same is designed for use, what I claim as new and desire to secure by Letters Patent is:—

1. A valve comprising a casing, a plug positioned therein having an annular socket, a valve removing member within said casing, and means for locking said plug to said 100 member engaging said socket.

2. A valve comprising a tubular casing, a sleeve removing means screw-threaded therein, a valve plug, means for locking said plug and sleeve, a head fitting said sleeve and 105 adapted for longitudinal movement therein, means for locking said head and sleeve against relative rotation, a cap encircling said plug, packing positioned between said cap and plug, and resilient means between 110 said cap and head.

3. In a valve, a valve stem having opposite shoulders thereon, a head having a central bore and positioned upon said stem, said head having a transverse slot upon the 115 bottom thereof intersecting said bore, and locking means positioned in said slot and engaging said stem shoulders.

4. A valve comprising a stem having opposite shoulders, a head having a central 120 bore for receiving said stem, a transverse slot upon the bottom of said head intersecting said bore, a carrier having an opening and a slot therethrough and adapted to be received upon said stem and engaging said 125 shoulders thereon.

5. In a valve, a tubular casing having drip openings therethrough, and a tapered seat, a plug positioned upon said seat and having fluid openings therethrough and a 130

central bore therein, a stem extending through said bore, a valve washer upon the end of said stem adapted to seat upon said plug, a removing sleeve positioned in said 5 casing, and means for locking said sleeve and plug.

6. In a valve, a tubular casing having drip openings therethrough, and a tapered seat, a plug positioned upon said seat and 10 having fluid openings therethrough and a central bore therein, a stem extending through said bore, a valve washer upon the end of said stem adapted to seat upon said plug, a removing sleeve positioned in said 15 casing, means for locking said sleeve and plug, a head mounted upon said stem, and means for locking said stem and sleeve against relative rotation, said head being slidably-positioned within said sleeve.
7. In a valve, a tubular casing having 20 drip openings therethrough, and a tapered

seat, a plug positioned upon said seat and having fluid openings therethrough and a central bore therein, a stem extending through said bore, a valve washer upon the 25 end of said stem adapted to seat upon said plug, a removing sleeve positioned in said casing, means for locking said sleeve and plug, a head mounted upon said stem, means for locking said stem and sleeve against 30 relative rotation, said head being slidably-positioned within said sleeve, a cap upon said plug, packing between said cap and plug, a helical spring between said cap and head, and a foot plate mounted upon said 35 head.

In testimony whereof I affix my signature in presence of two witnesses.

VICTOR D. RENWICK, JR.
